UNITED STATES PATENT OFFICE.

GEORGE MOEBS AND JOHN B. THIESEN, OF DETROIT, MICHIGAN, ASSIGNORS
TO BURK, MOEBS & CO., OF SAME PLACE.

DESIGN FOR CIGAR-BOXES.

Specification forming part of Design No. 5,942, dated June 18, 1872.

To whom it may concern:

Be it known that we, GEORGE MOEBS and JOHN B. THIESEN, of Detroit, in the county of Wayne and State of Michigan, have invented a new and useful Design for Cigar-Boxes; and we do declare that the following is a true and accurate description thereof, reference being had to the accompanying photographic illustration and to the letters of reference marked thereon and being a part of this specification, in which—

Figure 1 is a perspective view of our cartridge cigar-box closed, and Fig. 2 is a similar view of the same open.

Like letters refer to like parts in each figure.

The nature of this invention relates to the construction of cigar-boxes to simulate the regulation cartridge-box of the United States Army, as shown in the accompanying illustration, in which—

A is a wooden box, made to contain either fifty or one hundred cigars standing on end, and is provided with the cover B, hinged to the rear edge of the top. The box and cover are covered with black enameled paper, and the inner face of the latter may be ornamented with a paper covering having the letters U. S., an eagle and shield, or the coat of arms of

the United States printed thereon. C is a "flap," made of pasteboard, and covered with black enameled paper, hinged by a flexible fabric to the back of the box to simulate the flap of the regulation cartridge-box. The face of the flap may be ornamented with the letters U. S. in gold bronze, or they may be cut from gilt paper and pasted thereon. The flap is provided with a strap of elastic webbing secured to the inner face thereof, which may be brought under and behind the box to secure the flap in the closed position.

The body of the box being of wood complies with the provisions of the Internal Revenue Laws concerning cigar packages, while the cost is so low as not to materially affect the price of the cigars packed in it.

What we claim as our invention, and desire to secure by Letters Patent, is—

The design for a cigar-box simulating an army cartridge-box, substantially as herein described and shown.

GEORGE MOEBS.
JOHN B. THIESEN.
